UNITED STATES PATENT OFFICE.

JOHN PATON ROBERTSON, OF SAN FRANCISCO, CALIFORNIA.

HYDROCARBON-BURNER.

1,171,140.

Specification of Letters Patent.

Patented Feb. 8, 1916.

Application filed March 5, 1912. Serial No. 681,680.

To all whom it may concern:

Be it known that I, JOHN PATON ROBERTSON, a subject of the King of Great Britain, having resided in the United States one year last past and having declared my intention of becoming a citizen thereof, now residing in the city and county of San Francisco, State of California, have invented a new and useful Hydrocarbon-Burner, of which the following is a specification.

My invention relates to a novel construction of hydrocarbon burner which is adapted to be employed in conjunction with the lighter as well as the heavier grades of hydrocarbon and in connection with land, marine or any other kind of boiler furnaces and one of the principal objects of my invention is to devise a burner in conjunction with which novel means are employed for regulating the strength or length of the flame and also to provide a novel burner tip and regulating device therefor which will produce a complete atomization of the oil.

With the above in view, my invention consists of a novel apparatus for burning light or heavy grades of hydrocarbon or other oil, wherein the hydrocarbon preferably unmixed with air or other gases is preferably heated to the desired temperature, until it is discharged from the atomizer, novel means being provided for varying the length of the flame.

In carrying out my invention I do not desire to be limited to any particular degree of temperature to which I may heat the hydrocarbon, since I am aware that it is a common right to heat hydrocarbon to the desired degree by suitable heating mechanism and to force the same under any desired pressure to a point of utilization.

To the above ends my invention consists of a novel construction of burner tip having a conical aperture with which is adapted to coöperate a novel construction of conical regulating valve, said valve having its forward portion guided and seated in a novel construction of disk having ports therethrough and tangential passages coacting with said ports and with said tip, the latter being preferably countersunk at its discharge end in order to insure proper combustion at the front of the furnace.

My invention further consists of a novel construction of burner tip in which a desired number of ports open at any desired

angle into a valve controlled discharge passage.

It further consists of other novel features of construction, all as will be hereinafter fully set forth.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a longitudinal sectional view of a hydrocarbon burner embodying my invention. Fig. 2 represents a perspective view of the tip seen in Fig. 1 in detached position. Fig. 3 represents in detached position a plan view of the disk seen in Fig. 1.

Similar numerals of reference indicate corresponding parts in the figures.

Referring to the drawings, 1 designates a casing having a chamber 2 therein, which latter communicates with any suitable source of supply for the heated hydrocarbon.

3 designates a packing nut secured preferably in threaded engagement with the casing 1 and having a chamber 4 for packing or lubricating material, said packing nut 3 having a cap nut 5 secured thereto, which is provided with packing 6, the valve stem 7 passing through said packing nut and being in threaded engagement therewith, as indicated at 8, the exterior portion 9 of said valve stem carrying a handle or hand-wheel 10 thereon, which is secured thereon by the nut 11 and the pin 12 or other equivalent fastening devices.

13 designates calibrations or indicating data on the periphery of the hand-wheel 10, which are adapted to coact with the finger or pointer 14, whose free end terminates in proximity to said calibrations, whereby the amount of opening of the valve 15 can be at all times readily ascertained. A tube, 24, is secured at one end in the casing, 1, and has the valve-stem extending axially through it. A body 23, is secured upon the other end of said tube and has an outwardly flaring chamber, 25. A disk, 17, has an axial bore, 110

16, in which the valve-stem is journaled, and a rearward extension, 18, and said disk covers the outwardly-flaring chamber 25. The front face of the disk is formed with 5 an annular groove, 22, near its periphery, and ports, 19, are formed through the disk from said groove to the conical chamber 25. An annular recess, 21, is formed in the front face of the disk and surrounding its axial bore, and tangential grooves, 20, are formed in the front face of the disk, extending from the ports through the disk to the central recess. A burner tip, 26, has an annular-flange, 27, and has its rear face bearing 10 against the grooved and recessed front face of the disk, 17, and said tip has a conical axial seat, 28, for the conical valve 15 upon the valve-stem, which seat has an opening, 29, through the face of the tip. A coupling, 15 20 30, is internally screw-threaded to screw upon the externally threaded body 23 and has an inwardly projecting annular flange, 31, engaging the annular flange upon the tip, so that the latter can be drawn against 25 the disk and body, tightly securing the parts together.

When the parts are in assembled position, as will be seen from Fig. 1, it will be apparent that the valve rod or stem 7 has two 30 bearings, one being the threaded bearing in the nut 3 while its forward bearing is in the opening 16 through the disk 17, the conical extremity 15 of the valve being located in the valve seat 28 wherefrom it will be 35 apparent that upon the rotation of the handle 10 the flow of the heated oil through the pipe 24 and the orifice 29 can be regulated according to requirements, whereby the strength or length of the flame can be regulated or increased or diminished according 40 to requirements. It will be apparent that by locating the threaded connection of the rod 7 in the position seen in Fig. 1, the same is removed as far as possible from the heat of 45 the fire or flame and that there will be no liability of the same being injured thereby.

By my novel arrangement of tip, disk, nut and body portion for the sprayer or atomizing device which constitutes the 50 burner, the number of parts is reduced to a minimum and while my invention particularly relates to liquid fuel sprayers for burners in which the fuel is sprayed solely by the agency of pressure, I do not desire 55 to be limited thereto in every instance, since

by my novel construction cold thick oil may be sprayed with the same efficiency as any of the lighter heated hydrocarbon products and I therefore do not desire to be limited in the use of my invention to any particular 60 kind of hydrocarbon or boiler furnaces. By the employment of the finger or pointer 14 in connection with the calibrations 13 the desired adjustment or position of the valve can be ascertained at all times. 65

It will now be apparent that I have devised a novel and useful construction of a hydrocarbon burner which embodies the features of advantage enumerated as desirable in the statement of the invention and 70 the above description, and while I have, in the present instance, shown and described a preferred embodiment thereof which has been found in practice to give satisfactory and reliable results, it is to be understood 75 that the same is susceptible of modification in various particulars without departing from the spirit or scope of the invention or sacrificing any of its advantages.

Having thus described my invention, what 80 I claim as new and desire to secure by Letters Patent, is:—

A liquid hydrocarbon burner, comprising a tubular casing formed with an outwardly flaring chamber, a disk bearing upon the 85 forward end of said casing and having a rearward extension extending substantially through the flaring portion of said chamber, said disk having a central bore, a central annular recess in its outer face surrounding 90 said bore, an annular groove near its periphery and ports through its bottom opening into said groove, a burner tip having an exterior flange at its inner end and seated with its inner face against said disk to 95 cover said annular and tangential grooves and central recess, and provided with a conical central valve seat terminating in a diverging discharge port, a coupling adjustably connected with said casing and having 100 an inwardly projecting flange engaging the flange of said tip, the discharge port of said tip being located outwardly of said coupling, and a conical valve slidable through said bore and co-operating with said conical central valve seat. 105
